UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SHADE-HOLDER.

1,385,896.

Specification of Letters Patent. Patented July 26, 1921.

Application filed March 16, 1920. Serial No. 366,298.

To all whom it may concern:

Be it known that I, GEORGE B. THOMAS, a citizen of the United States of America, residing at Bridgeport, in the county of 5 Fairfield and State of Connecticut, have invented certain new and useful Improvements in Shade-Holders, of which the following is a specification.

My invention relates to shade holders, and 10 particularly to shade holders adapted to carry a plurality of shades or reflectors, the object of my invention being to provide an improved shade holder adapted to grip shades having necks of different diameters.

15 In the accompanying drawings—

Figure 1 is a vertical section through the shade in which my invention is embodied in one form showing portions of a pair of shades in assembled position;

20 Fig. 2 is a side elevation of the shade holder alone;

Fig. 3 is a perspective of one of the spring gripping rings; and

25 Fig. 4 is a perspective of the other gripping ring.

The present invention is particularly applicable to the type of shade holder illustrated, in which two shades or reflectors 5 and 6 are supported from the single shade 30 holder 7. As will be noted, the neck bead 8 of the inner shade holder 6 is of less diameter than the bead 9 of the outer shade 5, through which it is inserted in the assembled fitting. It is impossible to use supporting rings of 35 the same diameter to engage both shades unless the rings are of such reduced normal diameter that they do not fit properly within a holder 7 of sufficient diameter to accommodate both shades, and consequently 40 will not properly center the shades with relation thereto in the assembled fitting.

Moreover, were rings of such reduced diameter used, a much greater tension would be exerted on the bead 9 of the shade 5 of 45 larger diameter than upon the bead 8 of the shade 6 of smaller diameter at the neck. In fact the pressure on the bead 9 in such case might be so great as to cause injury to the shade under varying temperature conditions.

50 The present invention affords a shade holder of such character that supporting rings of the same size may be employed, and these rings may be of proper diameter to center the shades with relation to the holder 55 in the assembled fitting. As here shown the

holder 7 has an annular flange 10 slotted in different planes to receive the operating finger holds 11 and supporting bends 12 of the two spaced rings 13 and 14, each of the well known type shown in the Martin Re-issue Patent No. 13,324 of November 28, 1911. The lower ring 13 is of standard construction. The upper ring 14, which engages the bead 8 of the inner shade 6, however, has secured to its opposite sides reducing plates 65 15, which are curved to the contour of the ring. These reducing plates may be attached to the ring in any suitable way. I have shown lugs 16 offset from each end of the plate and folded around the ring. The 70 length of each reducing plate is such that the lugs 16 are located at an angle of 90 degrees to each other, so that when supporting strain is placed upon the plates there is no tendency to swivel on the ring. The inner 75 edges of the reducing plates 15 engage the bead 8 of the shade 6 and support the latter in precisely the same manner as a ring, while the latter is of sufficient diameter to properly center the shade with relation to the 80 holder 7 and to the outer shade 5.

While the same result might be accomplished by means of shade holding screws passed through the flange 10, the screws for the inner shade 6 being longer than those for 85 the outer shade 5, such screws have the obvious disadvantage of being inconvenient to manipulate, affording uncertain security, and inaccuracy of centering action.

While I have shown curved reducing 90 plates 15 secured to one of the shade holder rings, it is to be understood that my invention is not limited thereto, since it is possible to secure substantially the same result by bending in supporting loops on the ring, 95 which loops would engage the bead 8, while leaving the main body of the ring of the same overall diameter desired in order to secure the centering action. It is also possible to affix inwardly projecting studs to the 100 ring. But I prefer the construction shown to either of the forms just mentioned.

Various other modifications will occur to those dealing with the problem which do not depart from my invention.

105 I claim—

1. A shade holder comprising a plurality of spaced, contractile spring rings of substantially the same diameter, and reducing plates secured to one of said rings and pro- 110

jecting inwardly therefrom to afford a shade support of less diameter than the ring.

2. A shade holder comprising a plurality of spaced, contractile spring rings of substantially the same diameter, and arcuate reducing plates secured to opposite sides of one of said rings and projecting inwardly therefrom to afford a shade support of less diameter than the ring.

3. A shade holder comprising a contractile spring ring, and arcuate reducing plates having lugs folded over the ring, said plates projecting inwardly from the ring to afford a shade support of less diameter than the ring.

In testimony whereof I have signed my name to this specification.

GEORGE B. THOMAS.
